Des. 211,076
Patented May 21, 1968

211,076

REFLECTIVE SAFETY VEST OR SIMILAR ARTICLE

Gus W. Speridon, 113 Arroyo Drive,
South San Francisco, Calif. 94127

Filed Jan. 16, 1967, Ser. No. 5,442

Term of patent 14 years

(Cl. D2—27)

FIG_3

FIG_1

FIG_4

FIG_2

FIG. 1 is a front elevational view of a reflective safety vest showing my new design.

FIG. 2 is a rear elevational view thereof.

FIG. 3 is a top plan view thereof.

FIG. 4 is a side elevational view thereof.

I claim:

The ornamental design for a reflective safety vest or similar article, as shown and described.
